UNITED STATES PATENT OFFICE.

BERNARD COHEN, OF NEW YORK, N. Y.

DESIGN FOR A HEAD FOR FUR COLLARS.

SPECIFICATION forming part of Design No. 22,284, dated March 14, 1893.

Application filed February 2, 1893. Serial No. 460,783. Term of patent 7 years.

To all whom it may concern:

Be it known that I, BERNARD COHEN, a citizen of the United States, residing at New York city, in the county and State of New York, have invented and produced a new and original Design for a Head for Fur Collars, Muffs, &c., of which the following is a specification, reference being had to the accompanying drawings, forming part thereof.

- o Similar figures of reference indicate corresponding parts in both views.

Figure 1 is a perspective view of a head showing my design, with the skull or head proper in section; and Fig. 2 is a plan view of the head, these two views being deemed necessary to fully illustrate my design.

The design is to represent an animal's head used as an ornament for fur collars.

The leading features of my design are the rib-like figure which is produced in relief upon the muzzle and extends around the edge of the mouth, and the curved tongue lying upon the under jaw and having its central

portion and its tip curved upward above the teeth.

The head 10 is provided with a muzzle 11, made in semblance of the muzzle of a small animal, and the muzzle is composed of the usual upper and lower jaws 12 and 13, which are provided with teeth 13^a. A tongue 14 lies within the teeth of the lower jaw, and its central portion and its tip 14, are curved upward so as to be exposed in the mouth and extend above the lower teeth. Extending entirely around the edge of the mouth on both the upper and lower jaws is a rib-like figure 15, which appears in relief when viewed in plan.

I claim—

The design for a head for fur collars, herein shown and described.

BERNARD COHEN.
